UNITED STATES PATENT OFFICE.

FRANK T. PALMER, OF COSCOB, CONNECTICUT.

PORTABLE WOOD-SAWING MACHINE.

SPECIFICATION, forming part of Letters Patent No. 728,967, dated May 26, 1903

Application filed July 25, 1902. Serial No. 117,036. (No model.)

To all whom it may concern:

Be it known that I, FRANK T. PALMER, a citizen of the United States, residing at Cos Cob, county of Fairfield, State of Connecticut, have invented a new and useful Portable Wood-Sawing Machine, of which the following is a specification.

My invention has for its object to provide a simple and inexpensive portable wood-sawing machine which may be furnished with or without wagon-gear, the special desiderata being that the machine be light, strong, and durable, so that it may be drawn by horses over rough roads, across lots, or in the woods, anywhere, in fact, that a wagon can be taken, and will be ready to go to work in an instant, no staking out or setting up or lining up of the engine being required, the engine being permanently lined up with reference to the sawing mechanism and capable of working equally well if not in a perfectly horizontal position.

With these and other objects in view the invention consists in certain constructions and in certain parts, improvements, and combinations, which will be hereinafter described and then specifically pointed out in the claims hereunto appended.

In the accompanying drawings, forming part of this specification, Figure 1 is a side elevation of my novel wood-sawing machine as in use; Fig. 2, a plan view of the rear end of the frame and sawing mechanism, and Fig. 3 is a rear elevation.

A denotes the frame of my novel sawing machine, which is shown as consisting of a wagon-body provided with the usual longitudinal sides 10, cross-pieces 11, bottom *a*, and cross-bolts 12.

B denotes a wagon-gear of any ordinary or preferred construction upon which the frame is adapted to rest. As the special construction of the wagon-gear is not of the essence of my invention, it is deemed unnecessary to describe a wagon-gear in detail.

C denotes a saw carried by a shaft 13, journaled at the rear end of an extension of the frame and provided with a belt-pulley 14. The saw is driven by means of a belt 15, passing over pulley 14 and over a driving-pulley 16 on the shaft 17 of an engine D, which may be

of any ordinary or preferred portable type. The engine is shown as resting upon cross-bars 21, which in turn rest upon sides 10.

E denotes a carriage provided with grooved strips adapted to slide on V-shaped ways 18, formed on the upper edges of the longitudinal sides 10, near one end thereof. The carriage is shown as provided with pins 19, against which a stick of wood may rest in use and with a handpiece 20 for convenience in operation.

The operation of my novel sawing-machine will be perfectly obvious from the description already given, the important features of the machine, being that it is light, strong, and durable, inexpensive to build and maintain, capable of being placed in the woods or on uneven ground, anywhere that a wagon can be drawn, and that it is ready to go to work in an instant without much regard to what position it may be in, so that no time is lost in building a foundation or lining up. The longitudinal sides are made heavy enough so that in connection with the cross-pieces 11, bottom *a*, and cross-bolts they will form a perfectly rigid framework, which carries not only the engine, but the saw-shaft and the carriage, it being practically unimportant within reasonable limits to the operation of the machine in what position the frame may be placed. As soon as the machine has been drawn to the place of use the belt is placed on the pulleys, the engine started, and the machine is ready for use, the operation being precisely like other sawing-machines using a sliding carriage.

It will be particularly noted that owing to the engine being supported on the cross-bars 21 above the bottom of the wagon-body and the sawing apparatus on the rearward extension of said body the body of the wagon may be employed as a storage place for fuel or for the transportation of tools, luggage, &c., when moving from place to place, portions of such material or articles being placed, if desired, under the cross-bars which support the engine.

Having thus described my invention, I claim—

The combination with a wagon-body having sides and cross-pieces, said body being

also provided with a rear extension, cross-bars mounted on said sides, an engine mounted on said cross-bars, a shaft mounted in said extension and carrying a saw, said shaft being driven from said engine, and a sliding carriage mounted on the side bars adjacent said shaft, said engine and saw being so positioned as to leave said wagon-body free for

storage purposes below the cross-bars and engine.

In testimony whereof I affix my signature in presence of two witnesses.

FRANK T. PALMER.
